UNITED STATES PATENT OFFICE.

JOHN SCHOPEN, OF NEWARK, OHIO.

GAS COCK.

Application filed November 1, 1923. Serial No. 672,226.

To all whom it may concern:

Be it known that I, JOHN SCHOPEN, a citizen of the United States, residing at Newark, in the county of Licking and State 5 of Ohio, have invented a new and useful Gas Cock, of which the following is a specification.

This invention aims to provide a gas cock for a burner for gas and other fuels of a like sort which is so constructed that it may be adjusted readily without the use of tools, the device being simple in construction and devoid of complicated parts, the construction being such that a proper adjustment 10 of the gas supply may be attained readily, the burner preventing a wasting of the fuel when operated properly.

It is within the province of the disclosure to improve generally and to enhance the 15 utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in 20 the precise embodiment of the invention 25 shown can be made, without departing from the spirit of the invention.

In the drawings:

Figure 1 shows in side elevation, a device constructed in accordance with the invention; Figure 2 is longitudinal section on the line 2-2 of Figure 1, parts remaining in elevation; Figure 3 is a cross section on the line 3-3 of Figure 1; Figure 4 is a fragmental longitudinal section showing a modification; Figure 5 is a cross section on the line 5-5 of Figure 4.

In carrying out the invention, as shown in Figures 1, 2 and 3, there is provided a main tubular member 1 terminating in a tip 2 carrying a projecting needle valve 3, the tip having inwardly converging passages 4, located about the valve 3 and merging into a single inlet opening 5 at their rear ends, the opening 5 communicating with the bore 50 of the main member 1. The main member 1 is provided intermediate its ends and near to its rear end, with a wrench head 6 whereby the rear end of the main member 1 may be threaded at 7 into the gas supply pipe 8, the head 6 abutting against the forward 55 end of the pipe 8.

A sleeve 9 is threaded at 10 on the member 1, for adjustment longitudinally thereof, and is supplied with a burner orifice 11 controlled by the needle valve. At its rear end, 60 the sleeve 9 is equipped with a combined hand wheel and guard 12, whereby the sleeve may be rotated, the hand wheel including a disk like body 14 and a rearwardly extended peripheral flange 15 housing the wrench 65 head 6.

When the parts are arranged as shown in Figure 2, the gas or the mixture of gas and air, or other fuel, flows from the pipe 8, through the main member 1, through the opening 5 and the passages 4, the air and gas, or other fuel, moving into the chamber 16 which exists between the forward surface of the tip 2 and the rear surface of the forward end wall of the member 1, the fuel flowing about the pointed needle valve 2, through the burner orifice 11. By moving the sleeve 9 lengthwise of the member 1, through the instrumentality of the hand wheel 12, the needle valve 3 may be made to control the amount of gas passing through the orifice 11, and if desired, the flow of 70 gas may be stopped entirely. The flange 15 of the hand wheel 12, houses the wrench head 6 and it will be impossible to turn the member 1 accidentally by way of the wrench head 6, and loosen the connection between the member 1 and the pipe 8.

In Figures 4 and 5, the sleeve 17 is threaded at 18, as before on the main member 19, the sleeve 18 having a tapered nozzle 20 adapted to cooperate with a tapered needle valve 21 formed on the forward end of the main member 19, the main member discharging through lateral openings 22 formed 95 in the tapered portion of the member 19, to the rear of the needle valve. Aside from the modifications specified, the device depicted in Figures 4 and 5 is constructed 100 like the device delineated in the other figures, and operates in the same way.

I claim:

In a device of the class described, a tubular member provided at its forward end with a reduced projection and supplied in its forward end with an opening communicating with the interior of the tubular member, the tubular member being supplied intermediate its ends with an outstanding head, and being threaded externally both in front 105 of the head and to the rear thereof, a sleeve 110 threaded on the forward portion of the tubu-

lar member and having a combustion orifice controlled by the projection, the sleeve being supplied at its rear end with a wheel whereby the sleeve may be rotated, the wheel embodying a rearwardly extended annular flange, the head being housed within the flange of the wheel against undesirable access, the periphery of the head being spaced sufficiently from the flange of the wheel so that, through the instrumentality of the

head, the rear portion of the tubular member may be threaded into a support.

In testimony that I claim the foregoing as my own, I have hereto affixed my signature in the presence of two witnesses.

JOHN SCHOPEN.
